UNITED STATES PATENT OFFICE.

LEON MOREL, OF BESANCON, DOUBS, FRANCE.

APPARATUS FOR RAISING BEER, &c.

SPECIFICATION forming part of Letters Patent No. 355,619, dated January 4, 1887.

Application filed May 15, 1885. Serial No. 165,628. (No model.) Patented in France October 8, 1884, No. 164,620; in Belgium April 7, 1885, No. 68,432; in England April 9, 1885, No. 4,392; in Germany April 11, 1885, and in Austria July 1, 1885, No. 13,388.

To all whom it may concern:

Be it known that I, LEON MOREL, a citizen of the Republic of France, and a resident of Besancon, in the Department of Doubs, France, have invented certain Improvements in Apparatus for Raising Beer and other Liquids, (for which I have obtained a French Patent No. 164,620, dated October 8, 1884; Belgian Patent No. 68,432, dated April 7, 1885; British Patent No. 4,392, dated April 9, 1885, and Austrian Patent No. 13,388, dated July 1, 1885,) of which the following is a specification.

My invention consists of certain improvements in the construction of apparatus for raising beer and other liquids by compressed air, as hereinafter described.

In the accompanying drawings, Figure 1 is a vertical section of an apparatus containing my improvements. Fig. 2 is a sectional plan 20 on the line 1 2, Fig. 1. Fig. 3 is a side view, and Fig. 4 an edge view, of one of the details of the apparatus; and Figs. 5, 6, 7, and 8 are views illustrating the valve-operating devices in different positions.

The apparatus comprises, first, a cylindrical air-compressing chamber, A, in which air is to be compressed by water admitted under pressure at *a*; second, a dome, B, to which the compressed air from the chamber A is admitted when the check-valve *x* opens; and, third, a chamber, C, to which the compressed air from the dome B is admitted under pressure regulated by a loaded valve. From this chamber C the air is supplied through a tube, D, under pressure to the cask or vessel containing the beer or other liquid to be elevated. The chamber B serves as a reserve or a supplementary air-chamber, to maintain a pressure of air while the air-compressing chamber A is being emptied of the water contained therein, as hereinafter described.

The devices for automatically opening and closing the valves to renew the pressure of air in the chamber A are arranged at the bottom 45 of said chamber. A lever, *b*, pivoted at *b'* to a bracket, *b''*, on the bottom of the chamber, carries at its opposite ends valves *c c'*, which, by the tilting of the lever on its pivot, alternately open or close the water inlet and outlet 50 orifices *a* and *a'*. On this lever *b* is mounted a block, *d*, which is free to slide longitudinally

on the lever. The opposite ends of the sliding block *d* present inclines, which when the sliding rod is moved, as hereinafter described, are acted upon by fixed pins or studs *e e'* on the bracket *b''*. The sliding block *d* also carries a central projection or pin, *f*, adapted to be acted on by tappets or fingers *g g'*, attached to or forming part of a segment or tumbler, E, which is provided with a counter-weight and is mounted on a fixed pivot, *n*, on the bracket *b''*. By the tilting of this tumbler from one side to the other, as hereinafter described, the block *d* is pushed either to the right or to the left, so as to thereby bring its inclines into contact 65 with the fixed stud *e* or *e'*, and consequently depress the corresponding end of the lever *b* and close, say, the inlet-orifice *a* and simultaneously open the outlet-orifice *a'*, or vice versa.

The weighted tumbler E is provided with a curved arm or attachment, *h*, having a distance-plate, *h'*, Fig. 4, so as to thereby present a guide-groove terminated by two studs or projections, *h* and *h'*. Within this groove projects a horizontal arm, K, carried by a vertical stem or rod, T, which is tubular at its lower end, and is there guided on a fixed pin or spindle, *p*, on the base of the air-compressing chamber, while at the upper end it is 80 guided in a tubular projection, *t'*, on the top of the chamber. A float, F, is guided on this rod, and is free to slide thereon to an extent limited at the lower end by a stop, S, and at the upper end by another stop, S', on the rod. 85 In the top of the chamber is formed an air-opening, *v*, normally closed, as shown by full lines in Fig. 1, by a valve on a pivoted rod, *v'*, the outer end of which embraces the upper end of the rod T, and is adapted to be acted 90 on by a projection, *s*, thereon.

The communication between the chamber and the dome B is through the top of the tubular portion *t'*, which is closed by the check-valve *x*. The communication between the dome 95 B and the air-chamber C is adapted to be closed by a valve, *i*, the stem of which is in two parts, *j j'*, separated by an air-tight diaphragm, M, so as to allow a free operation of the valve without permitting any escape of air from the chamber 100 except through the pipe D, leading to the cask or vessel containing the beer or other liquid to

be elevated. The ends of the half-stems j, j' bearing against the diaphragm M are enlarged, as shown in Fig. 1, and the upper stem, j' , is acted on by a lever, G, provided with a movable counter-weight, P, by which the pressure on the valve i to close it to its seat may be varied to regulate the pressure under which the air is admitted from the dome B to the chamber C.

The operation of the above-described apparatus is as follows: Supposing the chamber A to be empty and the float F resting upon the lower stop, S, on the rod T, the tumbler E will be in the position illustrated in Fig. 5, and will have pushed the sliding rod d into such a position that the lever b will have been tilted over to open the inlet-opening a and close the outlet a' . Water will thereby be admitted to the chamber A, and as it gradually rises therein it will raise the float F, causing it to slide upward upon the rod T. At the same time, by the influx of water, the air in the chamber A and in the dome B will be compressed until it balances the pressure or head of water, which, for the sake of illustration, may be put at two atmospheres. When the pressure on the valve i allows, the air compressed in the dome B will raise the valve and thereby pass into the chamber C, and will thus be transmitted through the tube D to the cask where the liquid is to be elevated. In proportion as this liquid is withdrawn from its cask the internal pressure in the chambers A and B diminishes, and the water continues to rise in the chamber A to maintain the balanced pressure until the float F has come into contact with the stop S' and raises the rod T. As the rod is elevated the arm K thereon will come into contact with the stop k on the arm of the tumbler E, and thereby raise the latter, as shown in Fig. 6, until it just passes the center, when its weight will cause it to overbalance and fall into the position illustrated in Fig. 7. The tappet g then strikes the pin on the block d and pushes the latter forward to

tilt the lever b and close the inlet-opening a , and at the same time open the outlet a' . The stops s on the rod T will have come into contact with the arm of the lever v to open the air-inlet v and allow the water to run out through the opening a' . Communication will be cut off from the dome B by the automatic closing of the check-valve x . As the water flows out the float F will descend until it comes into contact with the stop S on the rod T, and causes the latter to descend to the position illustrated in Fig. 8. The arm K is thus caused to come into contact with the stop k' on the arm of the tumbler E and pull the latter over until its weight overbalances. It will then tilt over to the position illustrated in Fig. 5, thereby opening the inlet a and closing the outlet a' , when the operation will be repeated.

I claim as my invention—

1. The combination of the inlet and outlet openings of an air-compressing chamber, A, a lever, b , carrying the valves therefor, and a sliding block, d , having inclines and projections f , with fixed studs e, e' , tilting tumbler E, having tappets g, g' and a float and rod, and devices connecting the tumbler and rod, substantially as set forth.

2. The combination of the inlet and outlet opening of an air-compressing chamber and a lever carrying the valves therefor, with a tilting tumbler, E, devices whereby the latter operates the said lever, stops k, k' on the tumbler, a vertically-sliding rod, T, having an arm, K, and a float to act on the rod, all substantially as specified.

In testimony whereof I have signed my name to this specification in the presence of two subscribing witnesses.

LEON MOREL.
